(57) **CLAIM**

The ornamental design for a radio-frequency module for a communication device, as shown and described.

DESCRIPTION

FIG. 1 is a front elevation of an radio-frequency module for a communication device showing my new design;

FIG. 2 is a rear elevation thereof;

FIG. 3 is a right side elevation thereof the side opposite being a mirror image;

FIG. 4 is a top plan view thereof;

FIG. 5 is a bottom plan view thereof; and,

FIG. 6 is a bottom perspective view thereof.

The broken line showing of portions of the design is for illustrative purposes only and forms no part of the claimed design.
